STABILIZING MECHANISM FOR RAILWAY TRUCKS AND THE LIKE

Herbert E. Tucker, Chicago, Ill., assignor to James R. Cardwell, Chicago, Ill.

Application April 11, 1940, Serial No. 329,141

23 Claims. (Cl. 105—197)

This invention relates to bolster supporting mechanism for railway cars.

One of the objects of the invention is the provision of new and improved bolster supporting mechanism that is so designed that when used in connection with the conventional bolster supporting spring assembly, it will not only prevent undue harmonic movement of the spring assembly by friction mechanism but will permit a limited free resilient vertical movement of the bolster under all load conditions without operating the friction mechanism.

Another object of the invention is the provision of a new and improved bolster supporting friction spring unit which embodies friction means for preventing harmonic movement and has associated with this unit means that provide an initial resilient movement in the vertical vibration of the unit and spring assembly during the normal travel of the truck on the rails.

A further object of the invention is the provision of a new and improved stabilizing mechanism that, when in use on the self-aligning spring-plankless type of truck, will tend to hold the wheels and side frames in their intended relation and will properly align the parts after distortion in rounding curves.

Other and further objects and advantages of the invention will appear from the following description, taken in connection with the accompanying drawings, in which—

Fig. 1 is a side elevation of a railway truck, with parts in section and parts broken away for the sake of clearness, and showing the bolster in its uppermost position;

Fig. 2 is a horizontal section on the line 2—2 of Fig. 1;

Fig. 3 is a section similar to Fig. 1 showing only a portion of the side frame and showing the bolster in its lowermost position;

Fig. 4 is a section on the line 4—4 of Fig. 3;

Fig. 5 is a perspective view of the friction shoe;

Fig. 6 is a perspective view of the resilient member that engages the friction shoe;

Fig. 7 is a side elevation of a modified form of truck on which the device is employed, with parts in section and parts broken away;

Fig. 8 is a plan view of the construction shown in Fig. 7, with parts in section and parts broken away;

Fig. 9 is an end elevation of the truck showing the left side in section along the line 9—9 of Fig. 7 and showing the right side in section along the line 9a—9a of Fig. 7;

Fig. 10 is a side elevation of a modified form

of the invention, with parts in section and parts broken away;

Fig. 11 is a horizontal section on the line 11—11 of Fig. 10;

Fig. 12 is a section on the line 12—12 of Fig. 10; and

Fig. 13 is a perspective view of a modified form of spring cap used in connection with the invention.

Referring now to Figs. 1 to 6 of the drawings, the reference character 10 designates generally a railway truck having side frames 11 provided with a bolster opening 12 through which a bolster 13 extends. The bolster 13 is supported from the side frames 11 by a spring assembly 14 which comprises a plurality of helical springs 15. In the form of the construction shown, five helical springs are employed at each end of the bolster and these springs are confined between an upper cap or spring plate 16 and a lower base or spring plate 17. The base plate 17 is mounted on a spring plank 18 which in turn is supported on the lower chord or tension member 19 of the side frame beneath the opening 12.

In the conventional type of spring assemblies employing free-acting helical springs, harmonic action, due to inequalities in the rails or roadbed or flat portions on the wheel tread, will develop when the vertical movements of the truck frame synchronize with the natural or periodic vibration of the springs unless means be provided for preventing this movement. Usually, friction units are employed for this purpose. But the difficulty with friction means is that it does not permit of a proper free resilient limited initial movement of the parts.

The present invention seeks to eliminate this difficulty by the provision of friction means in combination with resilient mechanism for supporting the bolster that will prevent harmonic action of the springs and at the same time will permit an initial free resilient vertical movement of the bolster under any and all load conditions. The present invention contemplates the use of friction shoes which are carried by compressible members mounted on the side frames of the truck so that a limited amount of vertical movement of the bolster may be had by the compression of the compressible members before the friction means begin to function.

Any suitable mechanism may be employed for this purpose. In the form of the construction shown, which is by way of example only, the frame is provided with pockets 21 and 22 forming upper and lower shoulders 38 and 41 at the

upper and lower sides of the opening 12. Resilient compressible members, such as the rubber blocks 23, are mounted in these pockets. A friction shoe 25 is provided for each block. Each shoe has an inner or bottom wall 26, Figs. 4 and 5, which is V-shaped in horizontal section, that is, the wall has two flat portions arranged at an angle to each other to form a dihedral angle. The apex of this angle is inclined downwardly and outwardly and its lower portion is located between the corner springs on the adjacent side of the spring assembly, Fig. 2, thereby conserving space. An outwardly extending flange extends across the top as at 29, Fig. 5, and along the side edges of the wall 26, as shown at 28 and 27, to form a cavity or recess 31 for receiving the rubber block 23. The inner wall 26 of the shoe has its upper end inclined outwardly at an angle to the plane of the lower portion of said wall, as shown at 30, Fig. 3. The flange 29 engages over the upper end of the rubber block 23, as shown in Figs. 1 and 3. The flanges 26 and 27 taper upwardly as shown in Fig. 5. A central rib or internal flange 28, tapering upwardly, extends in the plane of the bisector of the dihedral angle formed by the two sections of the bottom wall, as shown more clearly in Fig. 5, and divides the recess 31 into the two recesses 32 and 33 at opposite sides of the rib. The rib or flange 28 does not extend outward to the plane of the outer edges of the flanges 26 and 27 so that the block 23 may rest on the rib 28 and be held in position by the flanges 26, 27 and 29.

The bolster 13 has its ends provided with side walls 34 which are V-shape, Fig. 4, and inclined inwardly and downwardly. Attached to each of said walls is a wear plate 35, Fig. 4, which is V-shape in horizontal section and is adapted to engage a friction surface 40 on the face of the shoe 25. The wear plates 35 are held in position in a V-shaped recess in the bolster by any suitable means such as the bolts 36. In order to relieve the bolts 36 of shearing strains, the inclined walls 34 of the bolster are recessed at 50 and are slightly concave from top to bottom, as shown at 60 in Fig. 1, for receiving the blocks that are slightly convex longitudinally thereof on the side adjacent to the side walls 34 of the bolster. The recess 50 in each end of the bolster provides a flange 39, Fig. 1, which overhangs the friction plates 35 and limits their upward movement. The rubber block 23 is longer than the corresponding shoe so that a space 37, Fig. 1, is provided at each side between the shoes and shoulders 38 under normal conditions. The rubber block 23 is rectangular in both vertical and horizontal sections except that its top and side edges at its outer side are beveled off as shown at 42, 43 and 44, respectively, Figs. 2 and 6, for increasing the space into which the rubber block may be distorted.

When the load is light, the springs 15 will support the bolster so that its zone of resilient movement will be in a higher plane than when the load is heavier. In other words, with light loads, the zone of vertical vibration for the bolster will be above the zone of movement of the bolster with heavier loads. But, in all cases, there will be free vibration within predetermined limits of the bolster within those zones; that is, the bolster will move freely with the shoe during the upward movement of the vibration until the shoe contacts the shoulder 41 and downward until the shoe contacts the shoulder 38. Any movement beyond those limits will result in relative movement of

the shoe and friction plate and cause frictional resistance to the further movement of the bolster thus preventing harmonic movement of the bolster and spring assembly.

5 In the operation of the device, when the load is applied, there will be a limited free resilient movement or vertical vibration of the bolster before there is any relative movement between the shoes and friction plates. This initial movement 10 will compress the springs 15 and at the same time will tend to distort the rubber blocks 23. This resilient movement will continue until the shoes come in contact with shoulders 38 after 15 which the bolster 13 will move relative to the shoes thereby distorting the rubber block still further into the recesses 32 and 33 and the reaction of the rubber blocks will cause considerable friction between the friction shoes and the friction plates 35 and this friction will not only 20 resist further compression of the springs, thus assisting in supporting the load, but will prevent undue harmonic vibration of the springs. During the vibration of the springs 15 under load, the bolster will be permitted a limited free vertical movement by the rubber block which will 25 materially assist in absorbing shocks and vertical vibrations of small amplitude.

If the load be heavy, the springs 15 will be compressed and the downward movement of the bolster will force the shoes 25 laterally thereby 30 distorting the rubber blocks upwardly thus lifting the shoes so that they will support the load in such a manner that vibration of small vertical amplitude will be absorbed by the rubber 35 block the same as with light loads.

It is common practice in the building of railway cars for high speed service to provide means for automatically banking the bodies on curves in order to counteract or partially compensate 40 for the centrifugal force exerted on those bodies while traveling around curves. The present invention utilizes the resiliency of the supporting spring assembly and the stabilizing mechanism for accomplishing this function.

45 It will thus be seen that at all loads, there is a free resilient movement which is limited only by the contact of the shoes against the upper shoulders 41 or their contact with the lower shoulders 38. In other words, while the shoes 50 are out of contact with these shoulders, there will be no frictional relative movement between the shoes and friction plates. This free movement of the bolster will occur at all loads and under all conditions thereby cushioning the load 55 of the car during the vertical vibration of the spring assembly. This is considered an important feature of the invention because it cushions the load under all operating conditions. Furthermore, since rubber is a sound absorbing medium, the rubber blocks assist in absorbing sound 60 which is an important feature when the construction is used on passenger cars.

In the use of self-aligning trucks, that is, of 65 trucks having their side frames integral with the journal and with the side frames free from each other except as tied together by the axles and bolster, it is common practice to provide resilient means between the columns and the bolster ends for properly squaring and alining the parts after rounding curves. Due to the short leverage and the width of the bolster, however, this 70 righting or squaring of the bolster and axles is considerably retarded. In Figs. 7 to 9 is shown a modified construction of frame and bolster 75 in which the stabilizing mechanism is more

prompt and efficient in effecting restoration of the part.

Referring now to Figs. 7, 8 and 9, the truck 45 is of the self-aligning spring-plankless type comprising the axles 46 and 47 having the wheels 48 and 49 thereon, as is usual in such constructions. The axles 46 and 47 are provided at their outer ends with journal boxes 51 and 52 which are integral with the side frame member 53, Fig. 7. The sideframe members 53 are each provided with an upper chord member 54 and a lower chord member 55, which are connected together at their ends and are connected at their central portion by a column 56 or standard, which is of a depth or thickness much less than that of the chords 53 and 54, for providing clearance for the bolster arms on the inner sides of the frames, as will presently appear.

The bolster 57 is provided at each end with forwardly and rearwardly extending arms 58 and 59, respectively. While the arm 58 will, for the sake of convenience of description, be termed the forward arm, it is understood that the construction is symmetrical and the truck may run in either direction. The outer end of the bolster is provided with a curved recess 61 which provides a clearance for the column or standard 56, as shown in Fig. 8 of the drawings. The arms extend between the upper and lower chords and have interposed between their outer ends, spring assemblies 62 and 63 for supporting the bolster from the lower chord 55, the adjacent surfaces of the arms and chords being provided with spring seats for the spring assemblies 62 and 63. These spring assemblies may each comprise any suitable number of springs, two being shown in the drawings. The outer ends of the bolster arms 58 and 59 are guided in their vertical movement by guide mechanism 65 that also functions as means for automatically aligning the parts and for preventing harmonic action of the spring assembly. This mechanism is substantially the same as that employed in the form of the construction shown in Figs. 1 to 6 and comprises a recess 60 in which is mounted a rubber block 64 which corresponds to the recess 31 and the rubber block 23 in Fig. 1. Friction shoes 66 are also provided for embracing the rubber block 64 and engaging a wear plate 80 on the end of the bolster arms substantially the same as in the previous construction. This wear plate is V-shape in cross-section as in the previous construction and the ends of the bolster arms are similarly formed, as shown in Fig. 8. The side walls of the arms are provided with flanges 90 for engaging the side edges of the shoes 66 and wear plate 80 for positioning the same. Since the details of the construction and the function of the parts are substantially the same as those previously described, it is not thought necessary to further illustrate and describe the same.

In traveling around curves, the tendency is for the outer wheels to lag, in which event there will be a slight angular movement between the rigid arms 58 and 59 and the side frames and this, in turn, will tend to move the friction shoes 66 relative to the side frame or journal boxes 51 and 52 thereby distorting the rubber 64. When the truck travels onto the straight portion of the track, the distorted rubber at the ends of the arms 58 and 59 will tend to move the frames so that they will be normal to the bolster 57 thereby properly squaring the truck and aligning the part thereon. It will thus be seen that, in the form of the construction shown in Figs. 7, 10

8 and 9, the arms 58 and 59 will function as powerful levers for placing the rubber blocks under shear in rounding curves and the resiliency of these blocks will tend to yieldably hold the truck axles and bolster in parallel relation. The rubber blocks will also function to absorb the smaller shocks and also force the shoes into frictional contact with the friction plates 80, as in the previous construction.

In traveling around curves, the outer wheels of the truck tend to lag, especially on trucks in which the side frames are not rigidly connected together by a rigid frame. In such trucks, clearances are usually provided for permitting the axles and bolster to have a slight angular movement relative to one another. It is common practice to provide means of some type for squaring the parts after the truck has negotiated the curve and again reaches a straight track.

In the construction disclosed in Figs. 10 to 13, a novel mechanism is employed for stressing the resilient block in traveling around curves so that this resiliency will restore the parts back to normal position after the curve has been negotiated. In the form of the construction selected to illustrate one embodiment of the invention, the side frame 67, which is of the usual construction but may be of any suitable construction, has a top chord 68, bottom chord 69 and the columns 71 and 72 forming the bolster opening 73, as is usual in such constructions. The columns 71 and 72 are provided with pockets 74 and 75 in which is mounted rubber blocks 76 and 77, all of which is substantially the same construction, as shown in Figs. 1 to 7 and described above. Since the rubber blocks 76 and the shoes 78 are substantially the same and arranged in the same way as those already described and function in substantially the same manner, it is not thought necessary to repeat a detailed description of this stabilizing mechanism at this point.

The bolster 79 extends into the opening 73 and the ends thereof are provided with elongated recesses forming bearings 81, see Fig. 12, 45 which are curved in cross-section and extending transversely across the lower surface of the end of the bolster. A suitable spring assembly 82 of the usual construction is interposed between each end of the bolster and the upper flat portion 83 of the bottom chord 69 of the bolster, Fig. 12. A spring plate of any suitable or well known construction 84 may be provided on which the springs of the assembly are seated.

The assembly is provided with an upper spring 55 or trunnion plate 85 that has suitable spring seats for engaging the upper ends of the springs for positioning the same. The spring plate 85 has a rib 86, Fig. 13, extending transversely across its upper portion and is curved in cross-section to form a journal for engaging the bearing 81 in the end of the bolster. The forward and rear edges of the spring plate 85 are provided with upstanding flanges or lugs 87, Fig. 13, having aligned openings 88 therethrough. A friction plate 89 is interposed between the flanges 87 and the friction shoes 78, as shown in Figs. 10 and 11. The friction plates 89 are each provided with flanges 91 and 92 which extend longitudinally of the truck, Fig. 11, and are of sufficient length to engage the inner and outer sides of the columns 71 and 72 which will prevent the friction plates 89 from moving inwardly or outwardly but will permit them to move vertically. The back of each friction plate 89 is provided with a trunnion 93 which is adapted to en-

gage the openings 88 on the spring plate and which functions as a horizontal pivot about which the spring plate 85 is adapted to turn.

Referring now to Fig. 12, it will be seen that when the loaded car travels around curves and the bolster 79 is caused to move to the left, in Fig. 12, by centrifugal action, the bearings 81 will tend to move the journal 86 to the left in said figure, thus causing the spring or trunnion plate 85 to rotate about the trunnion 93 of the wear plate 89 thus causing the inner edge of the plate 85 to compress the inner springs 94 to a greater degree than the outer springs 95 and when the truck negotiates the curve, the springs 94, being stressed more than the springs 95, will tend to move the plate 85 and with it, the bolster 79, back to normal position with the trunnion 93 in the vertical plane of the journal 86. Simultaneously, with the excess stressing of the springs 94, the rubber blocks 76 will be distorted more on one side edge than on the other due to the fact that the outer wheels tend to lag in rounding curves. As a result of this arrangement, when the truck reaches straight away track, these blocks and the springs will tend to return the parts to normal position with the bolster normal to the side frame.

It will thus be seen that in all forms of the truck construction on which the stabilizer is employed, the rubber blocks are distorted when the truck bolster is angularly moved relative to the frame. The blocks are distorted in such a manner as to tend to move the parts back to normal position after the curve is rounded. It will also be noted that in all forms of truck construction disclosed, the stabilizing device not only functions to resist relative angular movement of the bolster and frames but that the parts are so constructed that there is a limited amount of free, resilient, vertical movement of the bolster at all loads before the friction shoes are caused to move, thereby providing easy riding under all load conditions.

It is thought from the foregoing, taken in connection with the accompanying drawings, that the construction and operation of my device will be apparent to those skilled in the art and that changes in size, shape, proportion and detail may be made without departing from the spirit and scope of the appended claims.

I claim as my invention:

1. In stabilizing mechanism for railway trucks, a friction shoe comprising an inner wall having a pair of friction faces arranged at an angle to each other on its front face so as to converge upwardly, both faces being inclined upwardly and rearwardly, a flange extending rearwardly about the top and side edges of the shoe to form a cavity opening rearwardly, and a rib within said cavity of less height than said flange for dividing said cavity into two recesses whereby a rubber block supported on said rib will be held in operative position by said flanges and may be distorted into said cavities.

2. In a railway truck, a side frame, having a bolster opening therein, a bolster within said opening, resilient means for supporting each end of said bolster, means for frictionally resisting harmonic movement of said resilient means beyond predetermined limits, said last named means comprising rubber members and friction shoes forced into frictional contact with said bolster and so constructed as to permit said bolster supporting means and shoes to move freely together between predetermined limits under all

load conditions and to frictionally resist relative movement between said shoes and bolster beyond those limits within any zone of vibration for said bolster.

3. In a railway truck, a frame, a bolster, springs for supporting said bolster from said frame, and stabilizing mechanism for said truck, said mechanism comprising resilient means and friction mechanism, said friction mechanism comprising shoes frictionally engaging said bolster and being so constructed that said resilient means will assist in supporting a load under all conditions but will prevent said friction mechanism from operating until said mechanism reaches its lowermost position on said truck.

4. In a railway truck, a frame, a bolster, springs for supporting said bolster from said frame, and stabilizing mechanism for said truck, said mechanism comprising friction shoes having inclined friction faces for engaging friction faces on said bolster, rubber blocks carried by said shoes, and means limiting the downward movement of said shoes and blocks for causing distortion of said blocks during the downward movement of said bolster, the distortion of said blocks absorbing the shocks to such an extent that said shoes will not function as friction means until they reach their lowermost position.

5. In a railway truck, a pair of axles, journal boxes for said axles, side frames rigid with said boxes, a bolster having laterally extending arms extending in the plane of said frames, friction surfaces on the ends of said arms, springs for supporting said arms from said frames, and means including friction shoes engaging said friction surfaces and rubber blocks carried by said journal boxes for forcing said shoes against said surfaces when said springs are compressed for resisting further compression of said springs, said rubber blocks being adapted to be distorted laterally when said truck rounds a curve and tending to restore the axles to normal position after passing around the curve.

6. In a railway truck, a pair of wheeled axles, journaled boxes for said axles, side frames carried by said boxes, said boxes having pockets, rubber blocks in said pockets, a bolster having forwardly and rearwardly extending arms from each end, friction means including friction shoes between said rubber blocks and the ends of said arms, said shoes being supported by said blocks a predetermined distance above the bottom walls of said pockets whereby said bolster will be partially supported by said rubber blocks during initial compression, and springs beneath said arms for assisting in supporting said bolster from said frame, said axles being movable angularly relative to said frames to a limited extent against the compression of said blocks.

7. In a railway car, a pair of axles, journal boxes on each of said axles at each end thereof, frames supported by said axles, rubber blocks mounted on said journal boxes, a bolster having forwardly and rearwardly extending arms, means interlocked with the ends of said arms for causing compression of said blocks when said axles move angularly to said frames whereby on rounding curves, said blocks will be compressed and on a straight track, the expansion of said blocks will restore the axles and bolster to parallel relation.

8. In a railway truck, a side frame having a bolster opening therein, a bolster extending in said opening, a column at each side of said opening, rubber blocks carried by recesses in said

columns, friction shoes mounted on and supported by said blocks, a spring assembly beneath the end of said bolster extending into said opening, a spring plate between said spring assembly and bolster, flanges extending upward along the sides of said bolster and having bearings therein, wear plates frictionally engaging said shoes and having trunnions engaging said bearings, means for pivotally connecting said bolster to said spring seat whereby when said bolster is moved endwise by centrifugal force on traveling around a curve, said spring plate will swing outwardly about said trunnions for compressing the inner springs more than the outer ones whereby said inner springs will tend to restore the parts to normal position after cessation of the centrifugal force.

9. A spring plate having spring seats on one side and having upwardly extending side flanges on the other, said flanges having bearing openings therethrough adjacent their upper edges, and a bearing rib curved in cross-section rigid with said plate and extending transversely to said flanges.

10. A railway truck comprising a pair of wheeled axles, journal boxes on the end portions of said axles, side frames carried by said journal boxes, a bolster having arms at each end thereof, said arms extending fore and aft adjacent to said journal boxes, resilient means for supporting said arms from said frames, and resilient connections between said arms and journal boxes for yieldingly resisting relative angular movement of said frames and arms in a horizontal plane.

11. A railway truck comprising wheeled axles, journal boxes for said axles, side frames supported by said journal boxes, a vertically movable bolster having arms extending fore and aft at each end thereof, resilient means for resiliently supporting the outer ends of said arms from said frames, and means engaging said arms and journal boxes for dampening the vertical vibration of said bolster, and for resiliently resisting relative angular movement of said arms and frames in horizontal planes.

12. A railway truck comprising wheeled axles, journal boxes on the outer ends of said axles, side frames carried by said journal boxes, a body supporting member extending transversely across said frames and having arms extending fore and aft along said side frames, resilient means for supporting said body supporting member from said frames, and resilient means for movably connecting said arms to said frames and for biasing said axles normal to said arms.

13. A railway truck comprising wheeled axles, journal boxes for said axles, side frames rigid with said journal boxes a bolster having rigid arms extending in opposite directions forwardly and rearwardly from said bolster along said frames to points contiguous to said journal boxes, and means carried by said journal boxes for movably connecting said arms to said frames, said means comprising resilient members for yieldingly resisting angular movement of said side frames relative to said arms.

14. In a railway truck, a frame, resilient mechanism supported by said frame, a bolster supported by said resilient mechanism, said mechanism including a spring assembly and a distortable unit, means permanently engaging said unit and frictionally engaging said bolster for limiting the resilient initial downward movement of said bolster upon the distortion of said

unit, said means frictionally resisting further downward movement of said bolster, said means being frictionally operative only after the initial downward movement of said bolster.

15. In a railway truck, a truck frame, a bolster, a spring assembly for supporting said bolster from said frame, friction shoes engaging said bolster for frictionally resisting relative movement of said shoes and bolster, resilient means for supporting said shoes so constructed and arranged that said shoes and bolster will move together for distorting said means during the initial downward movement of said bolster, means for limiting the further downward movement of said shoes without preventing the further downward movement of said bolster for causing the further distortion of said resilient means.

16. In a railway truck, a truck frame, a bolster, a spring assembly for supporting said bolster from said frame, friction shoes engaging said bolster for frictionally resisting relative movement of said shoes and bolster, compressible means for supporting said shoes from said frame, said means being compressed when said bolster and shoes move downwardly, means for limiting the downward movement of said shoes during the compression of said assembly, and means for causing the distortion of said compressible means when said bolster has been depressed beyond the limit of downward movement of said shoes.

17. In a truck, a spring assembly carried by said truck, car supporting means carried by said assembly, friction elements carried by said means, friction shoes for frictionally engaging said elements for frictionally resisting the downward movement of said means, distortable means adapted to be compressed by said shoes when said shoes move downwardly, and means for limiting the downward movement of said shoes to predetermined limits during the downward movement of said car supporting means without limiting the further downward movement of said last-named means.

18. In a railway truck, a side frame member, a bolster member, springs for supporting said bolster member from said side frame member, and stabilizing mechanism for said truck, means for supporting said mechanism from one of said members, said mechanism comprising resilient means and friction mechanism, said resilient means being compressible vertically for absorbing vibrations of small amplitude and moving independently of the operation of said friction mechanism under all load conditions and compressible laterally for forcing the parts of said mechanism into frictional contact, said friction mechanism comprising friction shoes carried by one of said members and frictionally engaging the other of said members, and means for limiting the downward movement of said shoes.

19. In a railway truck, a truck frame member, a bolster member, means for supporting said bolster member on said truck frame member, said means comprising springs, resilient units and friction mechanism, said friction mechanism comprising friction shoes engaging one of said members, means for limiting the downward movement of said shoes, said resilient units being compressible vertically and horizontally by said shoes and operating on vibrations of short amplitude under all load conditions, and said friction mechanism operating only after said resil-

ient units have reached the limit of their downward movement during their vibrations.

20. In a railway truck, a truck frame member, a bolster member movable relative to said frame member and a resilient unit between said bolster and frame members for assisting in supporting said bolster from said frame, said unit comprising a friction shoe frictionally engaging one of said members, a rubber block between said shoe and said other member, said rubber block resisting the initial downward movement of said bolster and simultaneously biasing said bolster to a predetermined angle relative to said truck frame member.

21. In a device of the class described, a supporting member, a supported member, a rubber block between said members, a friction shoe frictionally engaging one of said members, said shoe engaging said block for compressing the same during the initial downward movement of said supported member, means for limiting the downward movement of said shoe, the friction between said shoe and one of said members resisting any further downward movement of said supported member after said shoe has reached the limit of its downward movement, and means for restoring said supported member to normal position after release.

22. In a railway truck, a side frame having an upper compression member and a lower tension member for defining the upper and lower margins of a bolster opening, a column at each side 5 of said opening rigidly connected to said members, a bolster extending into said opening, a spring assembly beneath said bolster and having its lowermost portion seated on said tension member, a spring plate for said assembly 10 interposed between said bolster and said assembly, and means for causing said spring plate to tilt inwardly when said bolster moves outwardly under centrifugal action while said truck travels around curves.

23. A railway truck comprising wheeled axles, journal boxes for said axles, side frames supported by said journal boxes, a bolster having arms extending fore and aft of each end thereof, means for slidably connecting said arms to 15 said side frames, said means comprising friction elements for frictionally resisting vertical movement to said bolster when the same moves beyond a predetermined distance, and resilient means for biasing said bolster to a predetermined 20 angular position relative to said frame.

HERBERT E. TUCKER.
